UNITED STATES PATENT OFFICE.

HERMAN BACKMAN AND EDWARD L. BECKERLEG, OF CHICAGO, ILLINOIS, ASSIGNORS
TO VARIETY FIRE DOOR COMPANY, OF CHICAGO, ILLINOIS, A CORPORATION OF
ILLINOIS.

DOOR.

Application filed April 24, 1922. Serial No. 556,344.

To all whom it may concern:

Be it known that we, HERMAN BACKMAN and EDWARD L. BECKERLEG, citizens of the United States, residing in Chicago, in the county of Cook and State of Illinois, have invented a certain new and useful Improvement in Doors, of which the following is a full, clear, concise, and exact description, reference being had to the accompanying drawings, forming a part of this specification.

This invention relates to doors and though capable of a wide and varied range of uses, is particularly adapted for use as a fire door for elevator shafts and the like.

One object of this invention is to provide an improved collapsible door of the sliding type so constructed as to require a minimum operating space and so controlled as to render the operation thereof exceedingly simple and easy.

Another object is to provide a novel means for suspending and controlling the several door sections so that when the door is extended it will completely cover the door opening and when contracted the several sections will automatically assume a superimposed relation in planes parallel to the door opening.

Other objects and advantages will hereinafter appear.

One embodiment of the invention is illustrated in the accompanying drawings.

The views of the drawings are as follows:

Figure 1 is a front elevation of a door constructed in accordance with the present invention;

Figure 2 is a vertical section through the door taken substantially on the line 2—2 of Figure 1;

Figure 3 is a fragmentary horizontal section through one edge of the door and illustrating the guides therefor;

Figure 4 is a vertical, longitudinal section through the door supporting a drum on a somewhat larger scale;

Figure 5 is a fragmentary, horizontal, longitudinal section through one end of the drum on a still larger scale;

Figure 6 is a vertical transverse section taken on the line 6—6 of Figure 5;

Figure 7 is a vertical section taken on the line 7—7 of Figure 4 and drawn to the same scale as Figures 5 and 6;

Figure 8 is a fragmentary, horizontal section taken through the drum shaft;

Figure 9 is a transverse section taken on the line 9—9 of Figure 8.

For purposes of illustration the door is shown applied to the inner or elevator side of a wall 10 of an elevator shaft and completely covering the doorway 11 therethrough. In the present instance the door is made up of two substantially flat rectangular sections 12 and 13 each formed preferably of heavy sheet metal and each preferably provided with upstanding vertical flanges 14 and horizontal flanges 15. The sections are mounted for vertical sliding movement in parallel planes from their respective closing position to position above the doorway. For this purpose suitable guides 16 and 17 are secured adjacent the opposite sides of the doorway. Each guide is provided with an inner channel 18 for receiving a vertical shoe 19 secured to a vertical flange 14 of the upper door section and an outer channel 20 for receiving a vertical shoe 21 secured to a vertical flange 14 of the lower door section.

The door sections are supported and controlled in such manner that as one section is moved from its closing position to a position above the doorway the other section is automatically moved in a similar manner so that in the withdrawn position of the door the sections assume a superimposed relation. Various means may be employed for this purpose. In the present instance however, the lower door section is supported by means of a cable 23 preferably fixed as at 22 to the horizontal flange 15, thereof and passing over a pulley 24 and through the wall 10 to a rotatable drum 25. The pulley is mounted in a suitable bracket 26 secured to the wall. The upper door section is supported by means of a cable 27 fixed at one end to a pin 28 secured to the bracket 26. Cable 27 is threaded beneath a pulley 29 mounted in a bracket 30 carried by the upper door section, over a pulley 31 mounted in the bracket 26, and through the wall to the drum 25.

The drum is preferably hollow as shown in Figure 4 and is mounted between a pair of brackets 32—33 secured to the outer side of the wall. One end of the drum is supported by means of a shaft 34 fixed against

rotation in the bracket 32. Shaft 34 projects through a pair of spaced bearings 35 and 36, the former secured within one end of the drum and the latter secured intermediate

5 the ends thereof. The other end of the drum is preferably supported by a stub shaft 37 extending from a sleeve 38 fixed within that end of the drum and journaled in the other bracket 33. A coil spring 39 10 surrounding the shaft 34 tends at all times to rotate the drum in a clockwise direction (Figure 2). One end of the spring projects through the bearing 35 and is secured within a groove 40 in the hub portion thereof by 15 any convenient means such as a screw 41. The other end of the spring is secured to the fixed shaft 34. For this purpose a sleeve 42 is secured to the shaft and the end of the spring is firmly clamped within a groove 43 20 thereof by means of a plate 44.

The upper free end of each of the cables 23 and 27 are secured to the winding portion or reel 45 of the drum. The reel is preferably spirally grooved to receive the cables 25 and is preferably conical in form so that a uniform tension is maintained in the cables as the tension in the spring varies with the winding and unwinding operations. The tension in the spring is sufficient to raise the 30 upper door section from its closing position to its position above the doorway but the rotation of the drum and hence the movement of the upper section is controlled by the movement of the lower section.

35 Although the spring may be placed under such tension as to raise both door sections when the door is released it is preferably so tensioned as to merely counterbalance the combined weight of both sections. When 40 relieved of the weight of the lower door section however, by a manual raising of that section, the spring acts to raise the upper section.

45 The door may be provided with a latch of any appropriate construction for retaining the door in closed condition. The latch illustrated in Figure 1 is of a well known type and comprises a rotatable disc 46 conveniently mounted on the lower door section 50 and controlling the position of the latch bolts 47 and 48. The inner ends of the latch bolts are pivotally connected with the disc at points 49 and 50, respectively, above and below the axis of the disc. The bolts 55 extend laterally in opposite directions through suitable openings in the opposite vertical flanges 14 of the door section and are engageable beneath the fixed cam members 51 and 52 preferably secured to the 60 front faces of the guides 16 and 17, respectively. A tension spring 53 secured at one end to the disc and at the other end to the door section, tends to rotate the disc in a counter-clockwise direction (Figure 1) to 65 yieldably maintain the bolts in extended or

latching position. The disc may be rotated in the opposite direction to withdraw the bolts by means of a handle 54 secured to the disc.

To raise the door to open position it is 70 only necessary to pull upwardly on the handle 54. This will cause a rotation of the disc 46 in a clockwise direction (Figure 1) to withdraw the latch bolts 47 and 48. By a continued pull upwardly the lower door section 75 is raised to its withdrawn position above the doorway. This manual raising of the lower door section permits the spring 39 to rotate the drum 25 so as to effect an upward movement of the upper door section. In view of the cable and pulley connection between this section and the drum, the upper section moves upwardly only half as fast as the lower section so that both sections reach their uppermost positions above 80 the doorway at substantially the same time. To close the door it is only necessary to push downwardly on the lower section. As this section moves toward closing position it causes a rotation of the drum in the opposite direction against the influence of the spring 39, thus permitting the upper section to move downwardly by gravity.

Numerous changes may be made in the embodiment of the invention hereinabove 95 described without departing from or sacrificing any of the advantages of the invention defined in the following claims.

We claim:

1. In combination, a pair of closure sections one superposed above the other in closed position and both movable in the same direction to open position, a drum provided with counter-balancing means therefor, a spiral pulley mounted upon said drum, and 100 a flexible element having one end attached to the lower closure section and its opposite end fixed, said flexible element having looped connection with the upper closure section and wrapped on the spiral pulley between its ends.

2. In combination, a pair of closure sections one superposed above the other in closed position and both movable in the same direction to open position, counter-balancing means for said sections and a single flexible element having one end attached to the lower closure section and its opposite end fixed, and a pulley having looped connection with the upper closure section and cooperating loosely with said counter-balancing means between its ends.

3. The combination with a wall having a doorway of a pair of closure sections one superposed above the other in closed position and both movable in the same direction to open position, a winding element, and a flexible element attached at one end to the lower closure section substantially centrally between its opposite sides and fixed at its 125 130

opposite end, said flexible element having looped connection with the upper section substantially centrally between its opposite sides and wrapped upon the winding element between its ends.

4. The combination with a wall having a doorway of a pair of closure sections one superposed above the other in closed position and both movable in the same direction to 10 open position on one side of the wall, a drum mounted on the other side of the wall above the doorway, and a flexible element attached at one end to the lower closure section substantially centrally between its opposite sides and fixed at its opposite end, said flexible element having looped connection with the upper section substantially centrally between its opposite sides and wrapped upon the drum between its ends.
- 20 5. The combination with a doorway of a pair of closure sections for said doorway, a winding element, and a single flexible element cooperating with said winding element

and having connection with said closure sections substantially centrally between their 25 opposite sides, said winding element effecting differential movement of the sections in operation without obstructing the doorway.

6. The combination with a pair of closure sections one superposed above the other in 30 closed position and both movable in the same direction to open position of means for effecting a differential movement of said sections in operation and means in operative relation with said first means for setting up 35 a counter-balancing action to the differential movement of said sections varying with the varying vertical positions of the sections to counter-balance the sections throughout their movement.

In witness whereof we hereunto subscribe our names this 21st day of April, 1922.

HERMAN BACKMAN.
EDWARD L. BECKERLEG.
